MOTOR OPERATED MECHANISM

Sylvanus C. Shipley and Benjamin Cyr, Minneapolis, Minn., assignors to Minneapolis-Honeywell Regulator Company, Minneapolis, Minn., a corporation of Delaware

Application December 16, 1937, Serial No. 180,179

15 Claims. (Cl. 172—239)

This invention relates to a motor operated mechanism and more particularly to one of the type wherein an element is biased to one position and is moved against its bias and held in a second position by the continued energization of a motor.

In many arts, it becomes necessary to move a controlling element between two positions, one of which is a safe position and the other of which is an active position. An example of such an element is a valve controlling the flow of fuel to a burner. When the valve is closed, it is in a safe position inasmuch as the continued maintenance of the valve in that position does not cause an unsafe condition to be created. When the valve on the other hand is in open position, it is in an active but unsafe position inasmuch as if the valve continues in that position, the burner may cause an overheating of the device heated thereby. Another such example of an element which is movable between a safe and an unsafe position is an electric switch. Such a switch is often used to control heating apparatus or apparatus whose continued operation under some circumstances may be undesirable. Where such elements are controlled by power operated devices, which in turn are controlled by automatically electrically operated controlling systems, it becomes highly imperative that some means be provided for insuring that these elements are moved to their safe position in the event of power failure. It is, accordingly, a common practice in certain arts to have the element biased towards a safe position and moved by an automatically controlled electric motor to its active position, the biasing means being effective in the event of power failure to return the element to its safe position. An art in which this principle is used to a considerable extent is the valve art, particularly where the valves are used for the control of a heat producing medium. In this case, the motor operating the valve is thermostatically controlled.

One very serious difficulty which has been encountered, however, in such motorized valves is that it is necessary to maintain the motor continually energized when the valve is in its open position. This results in the motor heating up with the result that there is a tendency for the bearings to stick. Inasmuch as such a motor usually operates the valve through a reduction gear train, any tendency of the motor to stick, no matter how slightly, offers a decided resistance to the return of the valve by the spring, inasmuch as the spring, in order to return the valve, must

rotate the entire gear train and motor. By reason of the fact that the motor is connected to the high speed end of the gear train, it must be rotated at a relatively high speed. It is impossible to overcome this difficulty by merely increasing the tension of the spring since this in turn results in the necessity of a much larger motor, which in turn gives off more heat when maintained in its energized position. As a result of this situation, considerable difficulty has been experienced in the past with valves of this type sticking in open position and causing an excessively overheated condition, which in certain instances have resulted in fires.

It will be readily apparent that the same difficulty would be experienced in the operation of any element biased to a safe position by means of an electric motor.

An object of the present invention is to provide a device of this type wherein upon initial movement of the apparatus in the reverse direction, the element is disconnected from the motor so that the biasing means is able to return the element unimpeded by the motor.

A second object of the present invention is to provide means in such an arrangement to stop the return movement of the motor at a point such that sufficient lost motion will exist in the connecting means to insure the establishment of a maintaining circuit during the taking up of such lost motion.

Further objects of the present invention will be apparent from a consideration of the accompanying specification, claims and drawings, of which:

Figure 1 is a vertical sectional view of the motor operated mechanism taken substantially along the line 1—1 of Figure 2;

Figure 2 is an end elevational view of the same looking from the left in Figure 1 and showing the cover for the mechanism in section, the section being taken along the line 2—2 of Figure 1;

Figure 3 is a side elevational view looking from the right in Figure 2 with certain portions being shown in section along the line 3—3 of Figure 2 and with the terminal block and binding post being shown in broken lines as though transparent;

Figure 4 is a diagrammatical view of the structure shown in Figures 1 to 3 and including the electrical control system therefor, and

Figure 5 is a detailed view of a portion of the valve operating mechanism in the position it assumes when the valve is in its open position.

While the invention is not so limited, the same has been illustrated as applied to the operation

of a valve for controlling the flow of gas to a burner.

Referring now to Figures 1 to 4, the control valve generally designated at 9 has a valve casing 10 having outlet and inlet openings 11 and 12, respectively. The valve casing 10 has a transverse wall 13 having a port opening 14 therein which is encompassed by an annular shoulder to form a valve seat 15. The valve member comprises a valve disc 16 adapted to seat on the annular seat 15, reinforcing washers 17 and 18 flanking the valve disc 16, said valve disc 16 and said reinforcing washers 17 and 18 being securely clamped together by means of a plug 19 and a nut 20 screwed thereon.

Extending into the plug 19 of the valve member is a valve stem 21, the plug 19 and the valve stem 21 having holes to receive a pin 22 to secure the valve stem 21 and plug 19 together in fixed relation. Mounted in an annular groove in the valve stem 21 is a split ring 23 which supports a spring retainer member 24. A spring 25 rests in the spring retainer member 24 and abuts against an abutment plate 26 to normally urge the valve member toward its seat. Located adjacent the upper portion of the valve casing 10 are a disc 27, a packing washer 28 and a support 29 which are secured together and to the abutment disc 26 by means of rivets 30. 31 designates a clamping nut, screw-threaded on the upper portion of the valve casing 10 to hold the support 29 in fixed relation to the valve casing 10.

Extending through the abutment disc 26, the disc 27, the washer 28, and the support 29 and secured thereto is a sleeve guide member 32 through which the valve stem 21 slidably extends outwardly from the valve casing 10. In order to effectively seal the valve 10 against leakage of fluid therefrom, a diaphragm 37 is secured to the outer end of the valve stem 21 by clamping the diaphragm 37 between a nut 34 and a washer 35, the clamping action being effected by a nut 36 screwed on the screw-threaded portion 33 of the valve stem 21. The outer edge of the diaphragm 37 is clamped between the support 29 and a base 38 by means of screws 39.

Mounted on the base 38 by means of screws 42 are two upright, spaced parallel plates 40 and 41, the plates 40 and 41 being held in spaced relation by bolts 43 cooperating with nuts 45 to clamp the plates 40 and 41 against spacer members 44.

55 A motor of any known type, generally designated at 46, is secured to and spaced from the vertical plate 40 by means of screws 47 and spacers 48. The motor shaft extends through the plate 40 and has a motor pinion 49 located on the end thereof. Located between the plates 40 and 41 and driven by the motor pinion 49 is a reduction gear train, comprising a gear 50 engaging the motor pinion 49, a gear 52 engaging a pinion 51 integral with the gear 50 and a gear 54 engaging a pinion 53 integral with the gear 52. The gears and pinions are suitably mounted and spaced between the upright parallel plates 40 and 41 by means of bearings 55.

70 By means of a pivot pin 59 and spacers 60, a lever 58 is pivoted between the plates 40 and 41 and by means of a pivot pin 61 and spacers 62 the lever 58 is pivoted to a U-shaped bracket 63, which bracket 63 is secured to the valve stem 21 by a nut 64 screwed on the screw-threaded

portion 33 of the valve stem 21 whereby movement of the lever 58 in a clockwise direction about its pivot pin 59 causes opening of the valve 9.

A pawl member 66 is pivotally secured by means of a pivot pin 67 to the lever 58. This pawl member intermediate the length thereof is provided with a shoulder portion 68 which is adapted to cooperate with a pin 69 secured to plate 40. The pawl member 66 is biased into engagement with pin 69 by means of a spring 70 surrounding the pivot pin 67 and which engages at one end the pawl member and at its other end a pin 71 secured to the lever 58. The pawl member 66 is also provided with a hook portion 72 at a point somewhat above the shoulder portion 68. This hook portion 72 is designed to cooperate with a pin 74 carried by the gear 54 in the low speed end of the gear train. The upper end of the pawl member 66 is bent forwardly as at 75 and has pivotally secured thereto a member 76. This member is provided with a transversely extending tooth engaging member 77, which under certain circumstances engages the tooth of the gear so as to disengage the hook portion 72 from pin 74. The member 76 is provided at its outer end with a curved extension 78 which is adapted to engage the fixed pin 43 to limit outward movement of member 76 and consequently of pawl member 66.

Secured to pawl member 66, as best indicated in Figures 1 and 2, particularly the latter, is a spring member 80. This spring member is rigidly secured at its lower end to the pawl member and is curved at 81 at its upper end. This curved upper end 81 of the spring member 80 is adapted to engage the pin 74 of gear 54 upon movement of the gear in valve closing direction.

The gear 54 is secured to a shaft 85. Also mounted on this shaft, as indicated in Figures 2 and 3, is a pair of collar members 86 and 87. Collar member 86 is rigidly secured to the shaft 85 whereas collar 87 is slidably but non-rotatably secured thereto. A cam member 88 is located between the collar members 86 and 87. A spring 89 bears against the collar member 87 and urges the same against the cam member 88 to clamp the same between collar members 86 and 87. In this manner, cam member 88 is frictionally connected to shaft 85 so as to rotate therewith when its motion is unimpeded. The cam member 88 is provided adjacent its upper portion with a notch 90 which is adapted to cooperate with a pin 91 secured to the plate 41. The pin 91 effectively serves to limit the movement of cam 88. Thus upon rotation of the motor in either direction, cam 88 is initially rotated until a respective shoulder of the notch 90 engages the pin 91. The cam member 88 is employed for actuating a maintaining switch. 60 This maintaining switch consists of a fixed contact carrying member 93 and a movable contact carrying member 94. Movable contact carrying member 94 is pivotally mounted to plate 41 at 95 and has attached thereto an elongated resilient member 96 which engages a pin 97 secured to a terminal plate 83. This terminal plate 83, which in Figure 3 is shown as if transparent, is secured to plate 41 by screws 82 and spacers 84. The resilient member 96 serves to bias contact carrying member 94 away from contact carrying member 93. Contact carrying member 94 is provided with a cam follower 98 which is adapted to be engaged by a toe portion 99 of cam member 88. Contact carrying mem- 75

bers 93 and 94 are provided with contacts 100 and 101, respectively, and upon the cam follower 98 engaging the toe portion 99 of cam member 88, upon clockwise rotation of the cam member, contacts 100 and 101 are moved into engagement with each other. The action of the maintaining switch is, accordingly, that upon initial movement of the motor in valve opening direction, contacts 100 and 101 are moved into engagement with each other, and upon an initial movement of the motor in valve closing direction, the contacts 100 and 101 are separated from each other. The function of this maintaining switch will be more apparent from the subsequent description.

Surrounding the mechanism is a cover member 105. This cover member slides over the edge of the base member 38 at its lower end and is held in position at its upper edge by a bolt and nut assemblage secured to plate 40 and generally indicated by the reference numeral 106. This cover can be conveniently removed when desired by unscrewing the nut of the fastening means 106.

The lever 58 projects through the cover 105, as indicated in Figures 1 and 3. The right-hand portion thereof, as viewed in these figures, is provided with a plurality of holes 108. These holes are for the purpose of attaching a chain, or similar member thereto, for operating a damper by means of lever 58. This function of the lever 58 is schematically illustrated in Figure 4. While the primary purpose of lever 58 extending through the cover is to actuate a damper, or other auxiliary apparatus, extension of the lever at the same time furnishes a means by which the valve may be manually actuated in the event of power failure. Inasmuch as it is undesirable that one inexperienced with the burner art operate the valve under such circumstances, the shoulder 68 is provided for the purpose of preventing such opening of the valve without removal of cover 105, as will be explained in more detail later. Upon removal of cover 105, shoulder 68 can be withdrawn from the path of pin 69 by engaging a thumb piece 110 on the pawl member 66. When this is done, it is possible by bearing down on the right-hand end of the lever 58 to move the valve towards open position. A plunger member 112 is provided for the purpose of holding lever 58 in its valve open position when it is so moved manually. The plunger 112 is slideable in a bearing member 113 and is provided at its inner end with a collar member 114 which is designed to be moved into the path of lever 58. A collar 115 of insulating material is secured to plunger 112. Extending between this collar 115 and a supporting plate 41 is a spring 116, which spring serves to bias plunger 112 to the position shown in Figure 2 wherein collar member 114 is out of the path of movement of lever 58. Secured to the terminal plate 83 is a fixed contact member 118. Cooperating with this contact member 118 is a movable contact member 119. Movable contact member 119 is biased into engagement with fixed contact member 118 but is normally prevented from moving into engagement with contact member 118 by reason of the collar 115 which is biased by the spring 116. It will be noted that collar 115 is in engagement with contact member 119 when the plunger is in its normal position shown in Figure 2. The contact members 118 and 119 form the two contacts of a

recycling switch, as will be more apparent from the subsequent description.

In Figure 4, a portion of the apparatus is shown schematically together with the control system for operation of the motor. The motor 46 is shown in the present figure as being of the shaded pole induction type. The motor comprises a stator core 125 upon which is located a field winding 126. The core 125 is formed with the two pole portions 127 and 128 which are split. Opposite halves of the two pole portions are provided with shading rings 129 and 130 of any conventional construction. A rotor 131 of the conventional squirrel cage type is rotatably mounted between the pole portions 127 and 128.

A thermostat is shown as forming the controlling switch. This thermostat is indicated generally by the reference numeral 135. This thermostat consists of a contact arm 136 which is secured to a bimetallic element 137. The contact arm 136 is designed to engage fixed contacts 138 and 139. The contact 138 is spaced farther from contact arm 136 than contact member 139. The result is that upon movement of contact arm 136 in the direction of contacts 138 and 139, the contact 139 is engaged first. Similarly, on movement of contact arm 136 in the opposite direction, the arm 136 separates first from contact 138. Bimetallic element 137 is arranged so that upon a temperature fall, the contact arm 136 is moved to the left.

Power is supplied for operation of the system by a step-down transformer 140. This transformer comprises a line voltage primary 141 and a low voltage secondary 142. The line voltage primary 141 is connected to line wires 143 and 144 leading to a suitable source of power (not shown). A switch comprising a switch blade 146 and a fixed contact 147 is provided for manually interrupting the power supplied to the motor 46 when it is desired to place the valve out of operation for a considerable period of time.

In this figure, the lever 58 is shown as connected to the secondary air damper of a gas burner. This damper is for the purpose of controlling the admission of secondary air to the burner. The damper is generally indicated by the reference numeral 150 and is pivoted to the casing 151 surrounding the gas burner. Only a portion of this casing is shown in the drawing. A chain 152 is shown as extending between the damped 150 and the lever 58.

The other elements of Figure 4 are shown schematically and correspond to elements shown and described in connection with Figures 1 to 3, and inasmuch as they bear the same reference characters as the corresponding elements in Figures 1 to 3, it is believed that a further description of these elements in connection with Figure 4 is unnecessary.

Operation

Various elements are shown in the position which they occupy when the thermostat 135 is in a position wherein it is not calling for the valve to be opened. Where the valve controls the flow of gas to a burner, as in the present instance, this position of the thermostat will be the position which it assumes when the temperature is above the desired value. Let it be assumed now that the temperature begins to fall by reason of the valve being closed. This will cause movement of contact blade 136 to the left causing it to successively engage contacts 139 and 138. The engagement with contact 139 has

2,242,990

no effect. As soon, however, as the engagement of contact 138 is effected, the following circuit is established: from the right-hand terminal of secondary 142 through conductor 155, contact 147, switch blade 146, conductor 156, conductor 157, contact 139, contact arm 136, contact 138, conductors 158 and 159, field winding 126, and conductor 160 to the other terminal of secondary 142. The result of the establishment of this circuit is that the motor becomes energized causing gear 54 to be rotated through the various elements of the gear train for reasons to be subsequently explained. The pin 74 at the time this movement is started will be in approximately the position indicated in solid lines in Figure 4. The rotation of gear 54 which will take place in a clockwise direction will result in the pin 74 similarly being moved in a clockwise direction away from hook 72. It will be readily apparent that upon slightly less than 360° of revolution of gear 54, the same will be brought into engagement with the under surface of the hook portion 72 of pawl member 66. Before, however, such engagement of pin 74 with hook portion 72 occurs, the cam member 88 will be moved in a direction to close contacts 100 and 101, as previously explained. The engagement of these contacts will result in a new circuit being established to field winding 126 as follows: from the right-hand terminal of secondary 140 through conductor 155, contact 147, switch blade 146, conductor 156, conductor 157, contact 139, switch blade 136, bimetallic element 137, conductor 162, contacts 101 and 100, conductors 163, 164, and 159, field winding 126, and conductor 160 to the other terminal of secondary 142. It will be noted that the last traced circuit is independent of contact 138. Thus, even though the temperature should rise slightly to cause disengagement of switch 136 with contact 138, the motor will not be stopped. It will thus be seen that the temperature differential is required between the stopping and starting of the motor. In this manner, any chattering of the thermostat will not result in rapid energization and deenergization of the motor.

As previously indicated, the continued rotation of gear 54 in a clockwise direction results in the engagement of pin 74 with the hook portion 72. As soon as such engagement takes place, further rotation of gear 54 results in pawl member 66 being raised upwardly and moving the valve towards open position. Due to the fact that the pin 74 follows an arcuate path, the pawl member 66 will be swung outwardly by the pin 74 thus enabling shoulder 68 to clear the stop pin 69. The position of pawl member 66 shortly after it passes pin 69 is shown in dotted lines in Figure 4. After shoulder 68 has thus cleared pin 69, the pawl member 66, the lever 58, and the valve will be free to continue to move upwardly. Such upward movement will continue until the lever 58 engages the pin 69, at which time the various elements will assume the position shown in solid lines in Figure 5, which corresponds to open position of the valve. The motor will be effective thereafter to continue to hold the valve, or other actuated element, in its uppermost position. It is to be understood that the gas admitted by the valve to the burner is lighted by a pilot light, or some other conventional igniting means.

At the same time that the valve is moved to its open position, a downward movement of the right-hand end of the lever 58 results in sec-

ondary air damper 150 being moved to open position. It will be noted that this damper is biased to open position so that as soon as the lower end of lever 58 moves down, the weight of damper 150 is able to move the damper to open position. The opening of the secondary air damper permits air to be admitted to the burner to support combustion.

The continued admission of gas to the burner by reason of the valve being held in open position eventually results in the temperature to which thermostat 135 is subjected rising to the point where the switch blade 136 separates not only from contact 138 but also from contact 139. When this occurs, both circuits to the motor field winding 126 are interrupted so that the motor is completely deenergized. The biasing spring 25 is thereupon effective to rotate lever 58 and, through the pawl member 66, the gear train and the motor in the reverse direction towards valve closed position. It will be noted that the under surface of tooth engaging member 77 is free of any sharp projections so that as long as the gear 54 is rotating in clockwise direction, the tooth engaging member 77 merely rides over the surface of the teeth. As soon as gear 54 starts to rotate in the reverse direction, the tooth engaging member 77 engages the teeth of gear 54 so that member 76 and consequently pawl member 66 are pushed to the left. It will be readily apparent that after such movement of pawl member 66 to the left continues for a relatively short distance, the hook portion 72 is disengaged from pin member 74, as shown in dotted lines in Figure 5. The disengagement of hook portion 72 from pin 74 effectively interrupts the connection between the valve and the motor and gear train. The result is that the valve, the lever 58, and the pawl member 66 are free to move downwardly independently of the gear train and motor. Moreover, such return movement is accomplished quite rapidly so as to insure an abrupt closing off of the gas to the burner.

Due to the fact that the gear train has some momentum imparted to it by the relatively limited motion thereof before the hook 72 is disengaged from pin 74, the gear train and motor will continue to rotate after such disengagement. If it were possible for pin 74 to clear the upper edge of hook member 72, pin 74 might well be left in a position to close to the under side of hook portion 72 that upon energization of the motor the engagement of pin 74 with hook 72 would take place before a maintaining circuit could be established by closure of contacts 100 and 101. Moreover, if such rotation continues sufficiently far in a counter-clockwise direction, it might engage pawl member 66 at the upper end thereof and move pawl member 66 outwardly so that shoulder 68 clears the pin 69, whereupon it would be possible for someone to manually open the valve without removal of the cover. In order to guard against either of these contingencies, the hook portion 72 is provided with an upper surface which is slightly recessed, as indicated at 167. Moreover, the spring 80 is provided which, as previously stated, has a curved end 81. Upon pin 74 rotating in a counter-clockwise direction after hook 72 has been disengaged therefrom, the pin 74 first strikes the spring 80. The effect of this spring is to yieldably halt further movement of the gear. In the majority of cases, pin 74 will never move into engagement with the upper surface of hook portion 72. However, if it does, it

engages the same and moves downwardly into the recess portion 167 so that any further movement thereof is effectively retarded. In this manner, it is assured that a substantial movement of the gear 54 is necessary upon reenergization of the motor before the pin 74 again engages the under side of the hook portion 72.

The amount of movement of gear 54 in the reverse direction which is required to move hook member 72 off of pin 74 is so slight that even if motor 46 has a decided tendency to stick, the chances are that such movement will still take place. Thus, the motor bearings may be sufficiently sticky that the valve would otherwise creep back a certain distance, and then by reason of the fact that the spring 25 would be under less tension, such movement of the valve would be stopped entirely. With the present invention, it is necessary to have only a small amount of such movement before the valve is disengaged entirely from the motor to assure closing of the valve. Due to the fact that spring 25 is most highly compressed when the valve is in fully open position, the probability is very great that a small amount of such movement will take place.

As previously indicated, it is considered undesirable in many instances for the average user to be able to manually open the valve by merely grasping the right-hand end of lever 58 and moving the same downwardly. For this reason, the shoulder 68 is provided which, if an attempt is made to open the valve in this manner, will engage pin 69 to prevent such movement. The service man or other person skilled in the operation of the equipment, however, can manually open the valve by merely removing the cover 105. When the cover is removed, it is possible to manipulate the thumb piece 110 to swing the pawl 66 to the left and move shoulder 68 out of the path of pin 69. It is then possible to move the valve to open position by depressing the right-hand end of lever 58.

The outer portion of member 76 is curved outwardly as at 78, as previously indicated. This outwardly curved portion is designed to engage with pin 43 so that when thumb piece 110 is manually manipulated, there is no danger of pawl 66 being moved so far to the left that the toothed follower 71 of member 76 rides off of the gear and drops down on the left-hand side of the gear.

As indicated previously, when the valve is opened by depressing the right-hand end of lever 58, the valve can be held open by moving the plunger 112 inwardly causing collar member 114 to be moved under the end of lever 58. Collar 114 and plunger 112 are held in this inward position against the biasing spring 116 by reason of the friction between collar 114 and lever 58.

When plunger 112 is moved inwardly to hold lever 58 in valve open position, the contact members 118 and 119 are moved into engagement. As previously indicated, these contacts constitute a recycling switch. The purpose of this is to insure that the valve is again placed under control of the thermostat as soon as power is restored. Closure of these contact members 118 and 119, as best indicated in Figure 4, results, as soon as power is restored, in the following energizing circuit to the field winding 126: from the right-hand terminal of secondary 142 through conductor 155, contact 147, switch blade 146, conductor 156, conductor 170, contact members 118 and 119, conductors 171, 164, and 159, field winding 126, and conductor 160 to the other terminal of secondary 142. It will be noted that the circuit just traced

is independent of the thermostat so as to insure that this circuit will be established immediately upon the restoration of power. While the position which the valve assumes when manually moved towards open position and held in this position by the plunger 112 has been previously referred to as the valve open position, this position is not the same as the complete valve open position to which the valve is moved by the motor. In other words, plunger 112 is designed to hold the left-hand end of lever 58 in a position where it is not entirely in engagement with pin 69. Accordingly, as soon as the motor is reenergized, the gear 54 is rotated so as to cause reengagement of pin 74 with hook portion 72 of the pawl member 66. The continued rotation of gear member 54 causes the lever 58 to be moved to the full open position shown in Figure 5. When this occurs, lever 58 is moved away from the collar member 114 so that plunger 112 is free to move to its normal position through the action of biasing spring 116. The movement of plunger 112 to the right results in a separation of contact members 118 and 119 so that the circuit last traced to motor field winding 126 is interrupted. The motor is thereupon again under the sole control of thermostat 135 and either stays energized or becomes deenergized, depending upon the then position of the thermostat.

It will be seen that the present invention provides an improved means of insuring the closing of a valve or other element biased to a safe position upon deenergization of the actuating motor, even though the motor or associated connecting elements offer such resistance to turning that the biasing means would not normally be able to completely move the operated element to its safe position. By reason of the device of the present invention, it is accordingly possible to obtain the advantages of a device which is biased to a safe position and moved to another position and held there only upon the continued energization of the actuating means and at the same time avoid the disadvantage thereof arising from the tendency of such mechanisms not to return to their safe position upon the deenergization of the actuating means.

While a specific embodiment of the invention has been shown for purposes of illustration, it is to be understood that the invention is limited only by the scope of the appended claims.

We claim as our invention:

1. In combination, an element to be operated movable between a safe first and an active second position, means biasing said element toward said safe first position, motor means, connecting means between said motor means and said element, said motor means being operative upon continued energization of said motor means to move said element toward and hold the same in said active second position, said biasing means being operative upon deenergization of said motor means to move said element, said connecting means, and said motor in the reverse direction toward said first position, and means operative in response to such movement toward said first position to render said connecting means inoperative, said last mentioned means being actuatable by energy of said biasing means whereby said element is returned by said biasing means to said safe first position independently of said motor means.

2. In combination, an element to be operated movable between a safe first and an active second position, means biasing said element toward said safe first position, motor means, a reduction gear

train having its high speed end connected to said motor means, connecting means between the low speed end of said reduction gear train and said element, said motor means being operative upon continued energization of said motor means to move said element toward and hold the same in said active second position, said biasing means being operative upon deenergization of said motor means to move said element, said connecting means, said gear train, and said motor in the reverse direction toward said first position, and means actuatable by such movement toward said first position to render said connecting means inoperative whereby said element is returned by said biasing means to said safe first position independently of said motor means and said gear train.

3. In combination, an element to be operated movable between a safe first and an active second position, means biasing said element toward said safe first position, motor means, connecting means between said motor means and said element, said connecting means comprising cooperating pin and hook members, one connected to said element and the other actuated by said motor means, said motor means being operative upon continued energization of said motor means to move said element toward and hold the same in said active second position, said biasing means being operative upon deenergization of said motor means to move said element, said connecting means, and said motor in the reverse direction toward said first position, and means responsive to such movement toward said first position to disengage said hook and pin members whereby said element is returned by said biasing means to said safe first position independently of said motor means.

4. In combination, an element to be operated movable between a safe first and an active second position, means biasing said element toward said safe first position, motor means, a reduction gear train having its high speed end connected to said motor means, connecting means between said motor means and said element, said connecting means comprising cooperating pin and hook members, said hook member being connected to said element and said pin member being secured to the gear at the low speed end of said gear train, said motor means being operative upon continued energization of said motor means to move said element toward and hold the same in said active second position, said biasing means being operative upon deenergization of said motor means to move said element, said connecting means, said gear train, and said motor in the reverse direction toward said first position, and means operative in response to such movement toward said first position to disengage said hook member from said pin member whereby said element is returned by said biasing means to said safe first position independently of said motor means and said gear train.

5. In combination, an element to be operated movable between a safe first and an active second position, means biasing said element toward said safe first position, motor means, a reduction gear train having its high speed end connected to said motor means, connecting means between the low speed end of said reduction gear train and said element, said motor means being operative upon continued energization of said motor means to move said element toward and hold the same in said active second position, said biasing means being operative upon deenergization of said motor means to move said element, said connecting

necting means, said gear train, and said motor in the reverse direction toward said first position, and means operated by said gear train in response to movement thereof in the reverse direction to render said connecting means inoperative whereby said element is returned by said biasing means to said safe first position independently of said motor means and said gear train. 5

6. In combination, an element to be operated movable between a safe first and an active second position, means biasing said element toward said safe first position, motor means, a reduction gear train having its high speed end connected to said motor means, connecting means between said motor means and said element, said connecting means comprising cooperating pin and hook members, said hook member being connected to said element and said pin member being secured to the gear at the low speed end of said gear train, said motor means being operative upon continued energization of said motor means to move said element toward and hold the same in said active second position, said biasing means being operative upon deenergization of said motor means to move said element, said connecting means, said gear train, and said motor in the reverse direction toward said first position, and means associated with said hook member, engaging an element of said gear train, and operative in response to movement of said gear train in the reverse direction to disengage said hook member from said pin member whereby said element is returned by said biasing means to said safe first position independently of said motor means and said gear train.

7. In combination, an element to be operated movable between a safe first and an active second position, means biasing said element toward said safe first position, motor means, connecting means between said motor means and said element, said connecting means comprising cooperating pin and hook members, one connected to said element and the other actuated by said motor means, said motor means being operative upon continued energization of said motor means to move said element toward and hold the same in said active second position, said biasing means being operative upon deenergization of said motor means to move said element, said connecting means, and said motor in the reverse direction toward said first position, and means responsive to such movement toward said first position to disengage said hook and pin members whereby said element is returned by said biasing means to said safe first position independently of said motor means, and means for yieldably limiting the coasting of said motor and said gear train after said connecting means has been rendered inoperative. 40 45 50 55 60 65 70 75 80

8. In combination, an element to be operated movable between a first and a second position, means biasing said element toward said first position, rotary electrical motor means, a reduction gear train having its high speed end connected to said motor means, connecting means between said element and said gear train, said connecting means comprising a first member carried by said gear train at the low speed end thereof and a second member connected to said element and lying in the path of said first member when said gear train is rotated by reason of the energization of said motor, a control switch including a pair of insecurely engageable contacts, a maintaining switch movable to closed 75

position upon initial movement of said motor, circuit means operative upon engagement of said pair of contacts of said control switch to cause energization of said motor, second circuit means operative upon closure of said maintaining switch to establish a circuit to said motor independently of said pair of contacts, said motor means being operative upon continued energization of said motor means to move said element toward and 5 hold the same in said second position, said biasing means being operative upon deenergization of said motor means to move said element, said connecting means, said gear train and said motor in the reverse direction toward said first position, means operative in response to movement of said motor in the reverse direction by said biasing means to render said connecting means temporarily ineffective whereby said element is returned by said biasing means to said first 10 position independently of said motor means, and means for terminating the coasting movement of said gear train before the first member of said connecting means carried thereby is in a position where forward movement thereof would 15 cause immediate engagement of the second member of said connecting means therewith whereby it is necessary for a sufficiently large movement of said motor and gear train to take place before engagement of said members of said connecting 20 means that the closure of said maintaining switch is assured prior to the engagement of said members.

9. In combination, an element to be operated movable between a first and a second position, 35 means biasing said element toward said first position, rotary electrical motor means, a reduction gear train having its high speed end connected to said motor means, connecting means between said element and said gear train, said connecting means comprising a first member carried by said gear train at the low speed end thereof and a second member connected to said element and lying in the path of said first member when said gear train is rotated by reason 40 of the energization of said motor, a control switch including a pair of insecurely engageable contacts, a maintaining switch movable to closed position upon initial movement of said motor, circuit means operative upon engagement of said pair of contacts of said control switch to cause 45 energization of said motor, second circuit means operative upon closure of said maintaining switch to establish a circuit to said motor independently of said pair of contacts, said motor means being operative upon continued energization of said motor means to move said element toward and hold the same in said second position, said biasing means being operative upon deenergization of said motor means to move said element, said connecting means, said gear train 50 and said motor in the reverse direction toward said first position, means operative in response to movement of said motor in the reverse direction by said biasing means to render said connecting means temporarily ineffective whereby 55 said element is returned by said biasing means to said first position independently of said motor means, and means for terminating the coasting movement of said gear train at a point such that the two members of the connecting means 60 are in a relative position such that sufficient movement of the motor and gear train is required upon reenergization thereof before reengagement of said members to insure the closure of said maintaining switch before such 65 reengagement.

10. In combination, an element to be operated movable between a first and a second position, means biasing said element toward said first position, electrical motor means, connecting means between said element and said motor means, said connecting means comprising interengaging members, one driven by said motor means and the other connected to said element, a control switch including a pair of insecurely engageable contacts, a maintaining switch movable to closed position upon initial movement of said motor, circuit means operative upon engagement of said pair of contacts of said control switch to cause energization of said motor, second circuit means operative upon closure of said maintaining switch to establish a circuit to said motor independently of said pair of contacts, said motor means being operative upon continued energization of said motor means to move said element toward and hold the same in said second position, said biasing means being operative upon deenergization of said motor means to move said element, said connecting means, and said motor in the reverse direction toward said first position, means operative in response to movement of said motor in the reverse direction by said biasing means to render said connecting means temporarily ineffective whereby said element is returned by said biasing means to said first position independently of said motor means, and means for terminating the return movement of said motor at such a point that the two members of the connecting means are in a relative position such that sufficient movement of the motor is required upon reenergization thereof before reengagement of said members to insure the closure of said maintaining switch before such reengagement.

11. In combination, an element to be operated movable between a safe first and an active second position, means biasing said element toward said safe first position, motor means, connecting means between said motor means and said element, said motor means being operative upon continued energization of said motor means to move said element toward and hold the same in said active second position, said biasing means being capable upon deenergization of said motor means of moving said element, said connecting means, and said motor means in the reverse direction toward said first position, and means operative as a result of the deenergization of said motor means to render said connecting means inoperative whereby said element is returned by said biasing means to said safe first position independently of said motor means, said means operative as a result of the deenergization of said motor means being so constructed and arranged as to utilize the force of said biasing means to render said connecting means inoperative.

12. In combination, an element to be operated movable between a safe first and an active second position, means biasing said element toward said safe first position, motor means, a reduction gear train having its high speed end connected to said motor means, connecting means between the low speed end of said reduction gear train and said element, said motor means being operative upon continued energization of said motor means to move said element toward and hold the same in said active second position, said biasing means being capable upon deenergization of said motor means of moving said element, said connecting means, said gear train, and said motor in the reverse direction toward said first position, and

means actuatable by energy of said biasing means upon deenergization of said motor to render said connecting means inoperative whereby said element is returned by said biasing means to said safe first position independently of said motor means and said gear train.

13. In combination, an element to be operated movable between a safe first and an active second position, means biasing said element toward said safe first position, motor means, disengageable connecting means between said motor means and said element, said motor means being operative upon continued energization of said motor means to move said element toward and hold the same in said active second position, said biasing means being operative upon deenergization of said motor means to move said element, said connecting means, and said motor in the reverse direction toward said first position, and means actuatable by such movement toward said first position to disengage said connecting means whereby said element is returned by said biasing means to said safe first position independently of said motor means and gear train.

25 14. In combination, an element to be operated movable between a safe first and an active second position, means biasing said element toward said safe first position, motor means, connecting means between said motor means and said element, said motor means being operative upon continued energization thereof to move said element to said active second position, said biasing

means being operative to move said motor means, said connecting means, and said element in reverse direction when said motor means is deenergized in a manner to impart momentum to said motor means, said connecting means being of a 5 one-way type permitting freedom of movement of said motor means in reverse direction and means arranged to resist and limit the amount of movement of said motor means in reverse direction, said last mentioned means being ineffective 10 to resist movement of said element, connecting means and motor means toward said safe first position.

15. In combination; an element to be operated movable between a safe first and an active second 15 position; means biasing said element toward said safe first position, motor means, transmission means between said motor means and said element, means including said motor means and said transmission means effective to move said element to said active position and to hold the same there against the action of said biasing means, means including said biasing means for returning said element to said safe first position, and means operative in response to the initiation of 20 such movement toward said first position to release said transmission means whereby said element is returned by said biasing means to said safe first position independently of said transmission means. 25
